UNITED STATES PATENT OFFICE.

ROBERT LEWIS JOHNSON, OF HANLEY, ENGLAND.

DESIGN FOR A COVER-DISH.

SPECIFICATION forming part of Design No. 27,933, dated December 7, 1897.

Application filed October 23, 1897. Serial No. 656,219. Term of patent 3½ years.

To all whom it may concern:

Be it known that I, ROBERT LEWIS JOHNSON, of Hanley, Stafford county, England, have invented and produced a new and original Design for a Cover-Dish, of which the following is a specification, reference being had to the accompanying drawings, forming a part thereof, in which—

Figure 1 is a side elevation of a cover-dish embodying the features of my design, and Fig. 2 is a transverse section of the same.

The leading feature of the design consists in the formation of the body of the dish, in which the body presents a shallow, pronounced, outwardly-flaring upper surface, a bowl center connecting with the inner portion of the top surface and likewise with the base. The upper edge a of the body is practically vertical, and the outer surface is

curved inward from said edge a slight distance, as shown at a' , being then carried farther inward at a slight inclination, as shown at a'' . The inclined surface at its inner end meets a convexed surface a^3 , which is continued to the base a^4 . The shape of the cover conforms to the shape of the upper portion of the body and curved horizontally-located handles appear at the ends of the body. The decorations of the body and cover may be of any desired character.

I claim—

The design for a cover-dish herein shown and described.

ROBERT LEWIS JOHNSON.
